US00D546396S

(12) **United States Design Patent** (10) **Patent No.:** **US D546,396 S**
Matsuno (45) **Date of Patent:** **** Jul. 10, 2007**

(54) **PORTABLE LIQUID CRYSTAL GAME DEVICE**

(75) Inventor: **Shotaro Matsuno**, Tokyo (JP)

(73) Assignee: **Bandai Co., Ltd.**, Taito-ku (JP)

(**) Term: **14 Years**

(21) Appl. No.: **29/244,814**

(22) Filed: **Dec. 15, 2005**

(30) **Foreign Application Priority Data**

Jun. 22, 2005 (JP) 2005-018140

(51) **LOC (8) Cl.** **21-01**

(52) **U.S. Cl.** **D21/324; D21/328**

(58) **Field of Classification Search** ..... D21/330, D21/439, 324-333, 403, 440, 478; D14/496; 273/148 B, 457, DIG. 14, DIG. 24; 463/1, 463/29-35, 46, 47; 252/299.01, 582, 586, 252/301.16; 349/1, 16, 58, 61; 359/616, 359/617, 894, 895

See application file for complete search history.

(57) **CLAIM**

I claim the ornamental design for the portable liquid crystal game device, as shown and described.

DESCRIPTION

FIG. 1 is a top plan view of a portable liquid crystal game device of my new design shown in a closed state;

FIG. 2 is a left side view thereof shown in an open state;

FIG. 3 is a front elevational view thereof shown in the open state;

FIG. 4 is a right side view thereof shown in the open state;

FIG. 5 is a bottom plan view thereof shown in the closed state;

FIG. 6 is a rear elevational view thereof shown in the open state;

FIG. 7 is a perspective view thereof shown in the open state; and,

FIG. 8 is a perspective view thereof shown in the closed state.
